[57] CLAIM

The ornamental design for a storage container, as shown and described.

DESCRIPTION

FIG. 1 is a perspective view of a storage container showing my new design;

FIG. 2 is a rear elevation view thereof;

FIG. 3 is a sectional view thereof, taken along line 3—3 in FIG. 2;

FIG. 4 is a top end elevation view thereof;

FIG. 5 is a side elevation view thereof;

FIG. 6 is a front elevation view thereof;

FIG. 7 is a side elevation view thereof opposite that shown in FIG. 4; and

FIG. 8 is a bottom end elevation view thereof.
